UNITED STATES PATENT OFFICE.

LOUIS A. GREEN, OF PITTSBURGH, PENNSYLVANIA.

SWITCH STAND.

Application filed December 26, 1923. Serial No. 682,629.

To all whom it may concern:

Be it known that I, LOUIS A. GREEN, a citizen of the United States, and residing in the city of Pittsburgh, in the county of Allegheny and State of Pennsylvania, have invented or discovered the new, useful, and Improved Switch Stand, of which the following is a specification.

My invention consists in a new parallel-
10 throw switch-stand for railway use.

Although my invention is advantageously applicable for general railway use, I have more particularly designed the same for use in mine tracks and in connection with other
15 light-service railways.

The object which I have in view is the provision of a durable and efficient, yet inexpensive and simply constructed switch-stand, and which will be particularly adapted for use in the cramped spaces and small
20 clearances characteristic of railway tracks in mines, narrow tunnels or passages.

Generally speaking, my improved stand comprises a support or housing, usually
25 mounted on and spanning the space between adjacent ties, and in which is journaled a vertically disposed pivot shaft whose lower end is provided with a crank arm linked to the movable switch rail, while the intermediate portion of the shaft is provided with a
30 longitudinally slotted diametric opening engaged by one end of a bar whose other end is pivotally connected to the short end of the throw arm, the slot in the shaft permitting
35 the bar to freely accommodate itself to the arcuate movement of its end connected to the throw arm.

Other novel features of construction, and also of arrangement of parts will appear
40 from the following description.

In the accompanying drawings, Fig. 1 is an isometric view of my improved stand; Fig. 2 is a side elevation of the same; Fig. 3 is a sectional view taken along the line
45 III—III in Fig. 2; Fig. 4 is a detail view of the pivot shaft and connecting bar, and Fig. 5 is an inverted plan view of the stand.

The following is a detailed description of the drawings.

50 A represents the support or housing, preferably formed of plate metal, its ends resting on and spiked to the adjacent ties 1, while its intermediate portion is elevated to provide clearance for the stand mechanism.

55 At its center the housing is provided with

a vertically disposed bearing 2 in which is journaled the upper end of the pivot shaft B, the upward movement of the shaft being limited by its shoulder 3, a washer 4 being 60 preferably interposed between the shoulder and the lower end of the bearing 2. The upper extremity of the shaft B protrudes above the bearing and is threaded to receive the nut 5 to prevent the shaft dropping out of 65 the bearing, a washer 6 being interposed between the upper end of the bearing and the nut. The shaft is also pierced to receive the cotter pin 7 to prevent accidental unscrewing of the nut. 70

The lower end of the shaft B is provided with a radial crank arm 8 whose outer end is pierced for the pivotal connection of the switch rod C which links the crank arm to the movable switch rail in the usual manner. 75

The shaft B is provided with a diametric opening 9 which is slotted longitudinally of said shaft, and in which is seated the flattened inner end of a connecting bar D, the 80 bar being thus free to move up and down in said slot relative to the shaft. The end of the bar may be upset or enlarged, as at 10 or otherwise provided with means to prevent the end of the bar becoming accidentally disengaged from slot. 85

E is the throw-lever which is pivotally mounted at a point near one end by means of a bolt 11 extending through a hole in the throw lever and through a pierced ear or 90 bracket 12 on the housing A.

The long or handle end of the throw lever E is preferably weighted, as at 13. The short end of the lever E is curved inwardly and provided with a circular hole or bearing 14 in which is journaled and through which protrudes the circular outer end of the bar D, said end being threaded to receive the nut 15 and pierced for the cotter pin 16. 95

The short end of the throw lever is bent inwardly, as shown, so that there will be no binding of the end of the bar in its journal in the end of the lever.

It is evident that as the throw lever E is 100 swung from one side to the other, its point of connection to the outer end of the bar D will move through an arcuate path concentric with the pivotal connection of the lever E to the housing A, thus causing the bar D to move in a vertical plane, as well as a horizontal plane. 110

The resultant compound movement of the

bar is provided for by the slotted nature of the opening 9 in the shaft B, which permits the bar to shift or rock vertically without binding or cramping the rotary movement of the 5 shaft which results from the horizontal movement of said bar.

It is evident that my improved switch stand is of very simple construction, containing a minimum of parts, none of which 10 are in themselves complicated. Thus requisite strength and durability may be successfully embodied in an inexpensive mechanism which will function in a highly satisfactory manner, and without undue wear.

15 What I desire to claim is:—

1. In a switch-stand, the combination of a support, a vertically disposed pivot shaft journaled in said support, crank connection between said shaft and the movable rail of 20 the switch, said shaft being provided with a longitudinally slotted diametric opening, a throw lever, pivotally mounted on said support, and a bar having one end pivotally connected to the end of the throw lever 25 while the other end of said bar is slidably mounted in said slotted opening.

2. In a switch-stand, the combination of a support, a vertically disposed pivot shaft journaled in said support, crank connection between said shaft and the movable rail of 30 the switch, said shaft being provided with a longitudinally slotted diametric opening, a throw lever pivotally mounted on said support, and a bar having one end journaled in a bearing hole in the end of the throw lever while its other end is slidably engaged in said slotted opening.

3. In a switch-stand, the combination of a support, a vertically disposed pivot shaft journaled in said support, crank connection 40 between said shaft and the movable rail of the switch, said shaft being provided with a longitudinally slotted diametric opening, a throw lever pivotally mounted on said support, and a bar having one end pivotally 45 connected to the end of the throw lever while its other end is inserted into said slotted opening and is free to shift therein longitudinally of the shaft.

Signed at Pittsburgh, Pa., this 14th day 50 of December, 1923.

LOUIS A. GREEN.
